BATCH METER FOR CONCRETE MIXING APPARATUS

Alfred W. Slack, Plainfield, and Robert A. Snyder, Gillette Heights, N. J., assignors to Worthington Corporation, Harrison, N. J., a corporation of Delaware

Application June 7, 1952, Serial No. 292,282

23 Claims. (Cl. 259—163)

This invention relates generally to concrete mixing apparatus and more particularly to a batch meter used in conjunction with concrete mixing apparatus such as concrete mixers, pavers and the like for securing accurate, controlled, and uniform mixtures of concrete therein.

It has been found that in connection with public works programs, building construction, road construction, etc., requiring concrete, that the specifications relating to these contracts call for various types of concrete mixtures or slump of a certain consistency and quality. It is, therefore, necessary that contractors be able to meet these varying requirements and to be able to produce and reproduce with a fair degree of accuracy these requirements from batch to batch of concrete mixed in any particular type of concrete mixing machinery.

It has been found that this can be done for the same quantities of ingredients by controlling the number of revolutions which the mixing drum will make for the particular batch. To eliminate any human error that might develop in counting the necessary number of revolutions, it has been further found that a meter which acts in conjunction with the mixing drum may be used.

Accordingly, it is an object of the present invention to provide a batch meter which counts with the charging skip of a mixing drum, or with both the charging skip and the transfer chute when dual drum type mixers are being used which prevents discharge, from the drum or through the transfer chute, until the mixing drum has performed a predetermined number of revolutions in accordance with the desired result.

It is a further object of the present invention to provide a batch meter in which a setting rod operated in conjunction with the charging skip or transfer chute will set the meter automatically and will simultaneously provide means for activating a counter to determine the number of batches that are mixed during a period of operation.

With these and other objects in view, as may appear from the accompanying specification, the invention consists of various features of construction and combination of parts, which will be first described in connection with the accompanying drawings, showing a batch meter for concrete mixing apparatus of a preferred form embodying the invention, and the features forming the invention will be specifically pointed out in the claims.

In the drawings:

Figure 1 is a diagrammatic sketch showing the invention with a single mixing drum;

Figure 2 is a front view of the batch meter;

Figure 3 is a side view partially in section on line 3—3 of Figure 2;

Figure 4 is a diagrammatic sketch showing a modified form of the invention used with a dual mixing drum;

Figure 5 is a side view in partial section showing the modified form of the invention.

Referring to the drawings, the batch meter arrangement with a single drum is diagrammatically illustrated in Figure 1 of the drawings showing a mixing drum 1 having a charging skip 2, only a fragment of which is shown, and a discharge chute (not shown) which is operated by a discharge chute lever 3. It will be understood that while the discharge chute lever is shown as being a manual type lever, it is obvious that the discharge chute could be operated by other devices and controls without departing from the spirit of this invention.

The charging skip or loader 2 is pivotally mounted and movable with a pivot shaft 4 having connected thereon a kick-out lever 5, so that as the skip 2 is raised and lowered the kick-out lever 5 will be moved relative to these respective positions.

Figures 1 and 2 further show the batch meter generally designated 6 mounted adjacent the mixing drum 1 by any suitable means. The batch meter 6 includes a substantially rectangular box-like housing 7 in which a setting or locking bar 8 is slidably disposed, parallel to the long axis thereof and extending outwardly of either side thereof. One side extending outwardly is connected through a connecting cable 9 about the pulley 10 to the end of the kick-out lever 5. The other side extending outwardly of the housing 7 is connected through levers 11 and 12 to a movable stop member or control device 13 which as shown in Figure 1 is adopted to abut a stop lever rod 14 on the discharge chute operating lever 3. It will be understood that while this type control is shown, that other types of controls actuated by the levers 11 and 12 could be used without departing from the spirit of the invention.

Thus, when the charging skip 2 is raised to load its contents into the mixing drum, the kick-out lever 5 is pivoted to actuate the locking bar 8 which, in turn, actuates the stop member 13 through the levers 11 and 12 to prevent the discharge chute (not shown) from being operated until the setting or locking bar 8 is released by

the automatic operation of the batch meter 6 as is hereinafter described.

The batch meter 6 includes a drive portion and a driven portion such that the drive portion is continuously rotated whenever the mixing drum 1 is rotated and the driven portion is brought into engagement with the drive portion for a predetermined number of revolutions. After the predetermined number of revolutions the driven portion actuates and releases the setting bar 8 so that the movable stop member 13 will be moved out of abutment with the stop rod 14 on the operating lever 3 to allow the operating lever or the like control to be operated for activating the discharge clutch (not shown).

Drive portion of batch meter

Accordingly, referring to Figure 2, a fragment of the mixing drum 1 is shown having a ring gear 15 disposed thereon to mesh and drive a pinion 16 which is fixedly connected to and hence in turn rotates shaft 17 and a bevel gear 18 connected on the end of the shaft 17 remote from the pinion 16.

As is shown in Figure 3, the shaft 17 and bevel gear 18 extend into a gear housing 19 formed and connected to the back wall 20 of the housing 7 of the batch meter 6. In the gear housing 19, the bevel gear 18 in turn engages a beveled pinion 21 connected to one end of a transverse shaft 22 mounted in said batch meter housing by bushings 23 and 24 perpendicular to the longer length of the housing 6.

A worm shaft support 28 as shown in Figures 2 and 3 is movably and rotatably mounted, on transverse shaft 22 for movement through an arc having the axial line of said transverse shaft as its center. Lateral brackets 26 and 27 on said worm shaft support 28 provide means for mounting a worm shaft 28 such that its axial line is perpendicular to the axial line of the transverse shaft 22. A worm 29 is provided on said worm shaft 28 and is rotatable therewith at all times.

The worm shaft 28 is rotated by miter gears 30 and 31, one miter gear 30 being disposed on the end of the worm shaft 15 so that its beveled face is at all times in engagement with the other miter gear 31 on the transverse shaft 22 in the arc of movement of the worm shaft support member 25, all of which is clearly shown in Figures 2 and 3 of the drawings.

Thus, whenever the mixing drum 1 is rotated the ring gear 15 will drive the pinion 16 which in turn drives the shaft 17 and bevel gear 18. The bevel gear 18 meshing with the beveled pinion 21 rotates the transverse shaft 22 connected to the pinion 21 and the miter gear 31. The miter gear 31 in turn rotates the miter gear 30 and shaft 28 so that the worm 29 is always rotating whenever the mixing drum 1 is rotating.

The worm shaft support member 25 is connected to and movable with the setting or locking bar 8 through a connecting spring 32 connected between the worm shaft support 25 and a fixed projection 33 on the setting or locking bar 8. The setting or locking bar 8 normally urges the worm shaft support 25 to the released or non-engaged position with respect to the driven portion hereinafter described as is indicated by the phantomized dotted portion in Figure 1 of the drawings. This is done by means of a setting bar spring 34 mounted about the setting bar 8 and abutting at one end the inner wall of the housing 7 and at the other end a washer 35 and

pin member 36 extending through the setting or locking bar 8.

When the setting or locking bar 8 is actuated by the kick-out lever 5 as above described it will move the worm shaft support member 25 from the released or non-engaged position to the locked or set position. This movement will be limited by a stop member 37 which projects laterally from the worm shaft support 25 which abuts a threaded adjusting means 38 held in any desired position by a locking nut 39 whereby the movement of the worm shaft support member 25 will be just sufficient to bring the worm 29 into engagement with the driven portion of the batch meter 6.

Driven portion of batch meter

The movement of the worm shaft support 25 is adjusted as above described to allow the worm 29 to engage gear teeth 40, cut on the periphery of a semi-circular quadrant 41 made of any suitable material. The quadrant is rotatably mounted on a quadrant shaft 42 disposed transversely with respect to the longer length of the housing 7 in a plane parallel to the plane of the transverse shaft 22. Figure 2 shows the quadrant 41 is weighted by any suitable means so that it will when not engaged by the worm 29 normally rotate to a position determined by abutment against a quadrant stop 43 of a movable adjustment clamp 44 adapted to be slidably positioned in an arcuate slot 45 on the face of the quadrant 41 by means of a threaded member 46 and thumbscrew 47. The movable adjustment clamp 44 will be set in accordance with the desired number of turns of the mixing drum required.

Thus, since the worm 29 is continuously operating whenever the mixing drum 1 is rotating, when it is in engagement with the teeth 40 of the quadrant 41, it will continue to rotate the quadrant 41 as long as it is in engagement therewith. The number of turns of the mixing drum 1 can therefore be measured in terms of the teeth 40 on the quadrant 41 and hence the desired arc of engagement predetermined for a given batch of concrete to be mixed in the mixing drum.

In order to set the movable adjustment clamp 44 one face of the batch meter 6 is open, and a cover member 48 is accordingly provided for this face of the batch meter 6.

Locking and releasing the setting bar 8

A bracket 50 is mounted across the longer length of the housing 7 just inwardly of the open face thereof to receive a locking rod support 51 on which is mounted a locking rod 52 disposed perpendicularly to the axial line of the setting and locking rod 8. The locking rod 52 is normally urged towards the setting bar 8 by a locking bar spring 53 mounted about the locking rod 52 and abutting a locking bar trip 54 fixedly connected and movable with the locking rod 52 at one end and the locking support 51 at the other end. In the released or non-engaged position the end of the locking rod 52 will be in sliding contact with a cam stop member 55 fixedly connected and movable with the setting bar 8, all of which is clearly shown in Figures 2 and 3 of the drawings.

When the setting or locking bar 8 is actuated the setting bar spring 34 is compressed and at the same time since the position of the locking rod 52 is fixed and it is merely in sliding engagement with the cam stop member 55, it will when the setting bar 8 has moved to bring the drive portion into the engaged position slip off the cam

stop member 55 into sliding engagement with the setting bar 8, and will prevent the return of the setting bar 8 under expansion of the setting bar spring 34 as it will now abut endwise with respect to the cam stop member 55. The setting or locking rod 8 will remain in this position until the locking bar 52 is released.

To release the locking rod 52 a quadrant lever generally designated 56 is provided. The quadrant lever 56 includes a substantially circular central portion 57, and extending therefrom releasing lever arm 58. The circular central portion 57 provides means for fixing the quadrant lever 56 to the face of the quadrant 41 by threaded members 59 so that the quadrant lever 56 is rotatable and movable with the quadrant 41. The releasing lever arm 58 extends laterally from the circular central portion 57 of the quadrant lever 56 and will be of sufficient length to adapt it to be brought into abutment with the locking rod trip 54 and to thereby move the locking rod 52 away from the setting bar 8 as the quadrant 41 is rotated until it is raised so that the cam face 60 of the cam stop member 55 is able to engage the end of the locking rod 52.

When this position is reached, the expansion of the setting bar spring 34 snaps the setting bar 8 over so that the worm 25 is instantly disengaged from the teeth 40 on the quadrant 41 to eliminate any possible injury thereto.

This also frees the quadrant 41 and allows it to rotate back to the predetermined stop position under action of gravity.

The setting or locking bar 8 is further provided with a spring 60' about the end of the locking bar where it extends outwardly of the housing to receive the connecting cable 9. The spring will engage a stop shoulder or washer member 61 fixedly mounted on the setting bar 8 to reduce the shock of the releasing action above described.

Counting device

Figure 1 shows a counting device 62 which is mounted on the inner wall of the housing 7 by means of a bracket 63. The counting device may be any suitable type, of which there are many easily purchasable on the open market, which registers by single units. The locking rod 52 is connected to the counting device by means of an elongated eccentric rod 64 connected between the upper end of the locking rod 52 and the actuating arm 65 for the counting device 62.

Each time the locking rod 52 is lifted to release the setting bar 8 one unit is registered on the counting device, each unit being the equivalent of one batch that has been mixed whereby a count of the number of batches mixed in a period of time or for a particular job, may be kept.

Auditory device

An auditory device is further provided to notify the operator that the number of revolutions are completed. This includes a bell 66 mounted in the inside of the rear wall 20, an L-shaped bell hammer 67 pivotally mounted at 68 in the angle formed by the legs thereof, a bell hammer spring 69, and a bell hammer trip 70 pivotally mounted and movable with the setting bar 8.

When the setting bar is actuated to move the worm 25 into engagement with the teeth 40 of the quadrant 41 as above described, the bell hammer trip 70 moves therewith pivoting so that it does not actuate the bell hammer 68. On the release of the setting bar 8 the bell hammer trip

70 moves again with the setting bar 8 but cannot pivot in the return direction. Accordingly, it trips the leg of the bell hammer 67 which is connected to the bell hammer spring 69 causing the bell hammer 67 and the bell hammer head 71 on the other arm to pivot away from the bell and to expand the spring 69 and then under action of the spring 69 to move the bell hammer 67 and head 71 towards the bell 66 and to strike it, to indicate to the operator that the number of revolutions have been completed. A bell hammer damper 72 is provided to prevent excessive oscillation of the bell hammer 67.

Modified form of the invention

It is believed obvious that where equipment has two or more drums that either two batch meters, one for each drum, or a single batch meter adapted to accomplish the same result by modifying it somewhat could be used.

This latter method is accomplished in the modified form of the batch meter shown in Figures 4 and 5, by expanding the widthwise dimension of the housing and adding the additional actuating, driving and driven means as is hereinafter described.

Referring to Figure 4, the modified batch meter 100 is shown in combination with a dual mixing drum 101 used in various types of road and building construction.

Dual mixing drum 101 includes a first compartment 102 and a second compartment 103 separated by a partition 104 having a transfer chute 105 mounted therein to transfer mixed ingredients from first compartment 102 to second compartment 103.

The transfer chute 105 is rotatably mounted by means of a shaft 106 and a spider 107, the shaft extending longitudinally of the drum and outwardly thereof to a formed lever arm 108 connected through rod 109 to the transfer chute hydraulic actuating means 110 receiving and returning operating pressure fluid through conduits 111 and 112 when the transfer chute control 113 actuates the hydraulic system (not shown). The hydraulic system is not shown as it forms no part of the present invention and any suitable hydraulic system may be used through the control 113 to actuate the transfer chute hydraulic operating means 110.

Compartment 102 receives the ingredients to be mixed from a charging skip or loader 114, only a fragment of which is shown in the drawings.

The charging skip 114 is pivotally mounted by means of a charging skip shaft 115. The skip shaft is provided with a kick-out lever 116 so that as the skip 114 is raised and lowered the kick-out lever 116 will be moved relative to these respective positions, as is shown on Figure 4 of the drawings.

The modified batch meter 100 is shown in the drawings as having a substantially rectangular box-like housing 118 in which a first and second setting or locking bars 119 and 120 are slidably disposed parallel to each other and to the long axis of the housing and of such length that they extend outwardly of either side thereof. The modified batch meter 100 is mounted adjacent the drum by suitable means as is clearly shown in Figure 4 of the drawings.

The end of the first setting or locking bar 119 extends outwardly of the housing on the skip side thereof and is connected by connecting cable 121 about pulley 122 to the kick-out lever 116. The other end of the setting bar 119 extending

out of the side remote from the skip side is connected through levers 123 and 124 to a transfer chute control stop member 125. The transfer chute control stop member 125 in the set position is abutted by the stop rod 126 attached to the transfer chute control 113 and the control cannot be operated until the stop member 125 is moved out of the set position, all of which is clearly indicated by the phantomized lines on Figure 4 of the drawings.

Similarly, the end of the second setting or locking bar 120 extending outwardly of the housing on the skip side thereof is connected through a connecting cable 127 about pulleys 128, 129, 130, 131 and 132 to the operating rod 109 of the transfer chute hydraulic operating means 110 so that when the transfer chute 105 is actuated the setting or locking bar 120 will be moved therewith. The other end of the second setting or locking bar 120 is connected through levers 133 and 134 to a discharge chute stop member 135.

The discharge chute stop member 135 in the set position is abutted by the stop rod 136 attached to the discharge chute control 137 and the control cannot be operated until the discharge chute stop member 135 is moved out of the set position, all of which is clearly indicated by the phantomized lines on Figure 4 of the drawings. The discharge chute control 137 operates the discharge chute operating means 138 connected through lever arm 139 and discharge chute shaft 140 to the discharge chute 141.

Thus, when the charging skip 114 is raised to load its contents into the first compartment 102, the kick-out lever 116 is pivoted to actuate the first setting and locking bar 119 which in turn actuates the transfer chute stop member 125 through the levers 123 and 124 to prevent the transfer chute 105 (normally closed) from being operated until the setting or locking bar 119 is released by the automatic operation of the modified batch meter as is hereinafter described.

When the first setting or locking bar 119 is released, the manual operation of the transfer chute operating lever 113 will rotate the transfer chute 105 to the transferring position by actuating the transfer chute hydraulic operating means 110. This causes the operating rod 109 to move downwardly and to pull the connecting cable 127 connected to the second setting or locking bar 120 to set the second setting or locking bar 120. The movement of the second setting or locking bar 120 in turn actuates the levers 133 and 134 connected to the discharge chute stop member 135 to prevent the discharge chute 141 (normally in non-transferring position) from being operated until the second setting or locking bar 120 is released by the automatic operation of the modified batch meter as is hereinafter described.

The portions of the modified batch meter for each compartment of the dual drum are substantially identical to those portions required for operation of a single drum. Thus, the modified batch meter is provided with two drive portions which are continuously rotated whenever the mixing drum is rotated and identical driven portions for engagement one with each of said drive portions. The driven portions as in the first described basic batch meter remain in engagement for a predetermined number of revolutions and thereafter actuate releasing and locking means for each of their respective setting bars so that the setting bar can be moved back to release either the transfer control stop means

or the discharge chute stop means connected to one or the other of the members being actuated.

Drive portions of modified batch meter

Accordingly, referring to Figures 4 and 5, the dual mixing drum 101 is shown having a ring gear 142 disposed thereon to mesh and drive a pinion 143 which is mounted on one end of 10 a shaft 144 extending into a gear case 145 where it receives a bevel gear 146 on the other end thereof. The gear case is mounted on the back wall of the housing 118 by bolts 147.

As clearly shown in Figure 5, the bevel gear 146 engages and drives a beveled pinion 148 connected to and rotatable with a transverse shaft 149 disposed perpendicular to the horizontal length of the housing 118 and mounted by suitable means such as a bushing 150 supported by a bracket 151.

Two worm shaft supports 152 and 153, identical except that they are the mirror images of each other, are movably and rotatably mounted on transverse shaft 149 for movement through an arc having the axial line of said transverse shaft as its center.

Since the worm shaft supports 152 and 153 are mirror images of each other, when mounted on the transverse shaft 149, they will have their lateral brackets 154 and 155 on work shaft support 152 and 156 and 157 on worm shaft support 153 extending towards and disposed adjacently to each other, as is clearly shown in Figure 5. These lateral brackets provide means for mounting a first worm shaft 158 and a second worm shaft support 159 therein such that their respective axial lines are perpendicular to the axial line of the transverse shaft 149. Worm members 160 and 161 are provided on each of 30 said worm shafts 158 and 159, respectively, and are fixedly connected thereto so that they will 35 continually rotate when said worm shafts 158 and 159 are rotating.

The worm shaft supports 152 and 153 are each 40 rotated by miter gears 162 and 163 for worm shaft support 158 and miter gears 164 and 165 for worm shaft support 159. Miter gears 162 and 164 are disposed on the ends of the worm shaft supports 158 and 159, respectively, adjacent the transverse shaft 149 so that the beveled faces thereof are at all times in the arcs of movement of the worm shaft supports 152 and 153, in engagement with its respective miter gears 163 and 165 fixedly connected and rotatable with the transverse shaft 149, all of which is clearly shown in 45 Figure 5 of the drawings.

Thus, whenever the dual type mixing drum 101 is rotated the ring gear 142 will drive the pinion 143 which in turn drives the shaft 144 and bevel gear 146 in the gear casing 145. The bevel gear 146 meshing with beveled pinion 148 rotates the transverse shaft 149 connected to the bevel pinion 148 and hence the miter gears 163 and 165 fixedly mounted on the transverse shaft 149. The miter gears 162 and 164 in turn rotate miter gears 162 and 164, respectively so that the shafts 158 and 159 connected thereto and the worm members 160 and 161 affixed to the shafts will 50 also be rotated.

Each of the worm shaft supports 152 and 153 are connected to and movable with its respective setting and locking bars 119 and 120 through connecting springs 166 and 167 connected between the ends of said worm shaft supports 152 and 153 remote from the miter gear ends and

fixed projections 168 and 169 on setting or locking bars 119 and 120, respectively. These setting or locking bars 119 and 120 as in the basic batch meter for single drum above described normally urge these worm shaft supports 152 and 153 to the released or non-engaged position with respect to the driven portion, hereinafter described. This is accomplished as in the basic batch meter for single drums above described by means of setting bar springs (not shown) which are mounted about the setting or locking bars 119 and 120 respectively so that they abut between the inner wall of the skip side of the modified batch meter housing 118 and pin members (not shown) inwardly of said wall on each of said setting bars 119 and 120.

When the setting or locking bar 119 is actuated by the kick-out lever 116 as above described, it will move the worm shaft support member 152 from the released or non-engaged position to the locked or set position. This movement will be limited by a stop shoulder 170 which projects laterally from the worm shaft support 152 which abuts a threaded adjustment means 171 held in any desired position by a locking nut 172 whereby the movement of the worm shaft support member 152 will be just sufficient to bring the worm 160 into engagement with one of the driven portions in the modified batch meter 100.

Similarly, when the setting or locking bar 120 is actuated by operation of the transfer chute hydraulic operating member 110 as above described, it will move the worm shaft support 153 from the released or non-engaged position to the locked or set position. This movement is likewise limited by a second stop member 173 which projects laterally from the worm shaft support 153 and which abuts a second threaded adjusting means 174 and locking nut 175 to limit the movement so that the worm 161 will just engage a second driven portion in the modified batch meter 100.

Driven portion of modified batch meter

The driven portion of the modified batch meter 100 includes semicircular quadrants 176 and 177, one for each of the worm members 160 and 161 and in alignment therewith, identical with those shown for the basic batch meter illustrated in Figures 2 and 3 of the drawings. The quadrants 176 and 177 are both mounted on a quadrant shaft 171 disposed transversely with respect to the longer length of the modified batch meter housing 118 in a plane parallel to the plane of the transverse shaft 149. Each quadrant is identical with those above described in the basic batch meter and are weighted to allow them to rotate to the desired position, suitable adjustment clamps and quadrant stops being provided therefor.

The movement of the worm support shafts 152 and 153 is adjusted as above described to allow the worms 160 and 161 respectively thereon to engage gear teeth 178 and 179 on their respective quadrants 176 and 177 for each of said worms 160 and 161.

The quadrants being identical with those described for the basic batch meter shown in Figures 2 and 3 can also be adjusted in accordance with the desired number of turns of the mixing drum required for the particular compartment in which the ingredients are being mixed.

Thus, since each of the worms 160 and 161 are continuously operating whenever the dual type mixing drum is rotating, when either of the

5 10 15 20 25

worms are in engagement with the teeth 178 or 179 of one or the other of the quadrants 176 and 177, then the quadrant will be rotated as long as it is in engagement therewith. The number of turns the mixing drum 101 makes for a particular compartment can therefore be measured in terms of the teeth 178 or 179 on the respective quadrants and accordingly the desired arc of engagement predetermined for a given batch of concrete to be mixed. For example, if a certain series of batches to be mixed require 200 turns, then the first batch will be loaded in the first compartment 102 for 100 turns and transferred to the second compartment 103 for another 100 turns. The first compartment will, of course, be reloaded after the transfer is made so that a new batch can be started through the dual mixing drum 100.

member. Whichever setting bar is so moved will be prevented from returning till its respective locking bar 188 or 189 is released. This operation and construction is, of course, identical for each setting bar as was described above and shown for the basic batch meter in Figures 2 and 3 of the drawings.

To release the locking rod 188 or 189, quadrant levers 196 and 197 are provided. The quadrant levers 196 and 197 are identical in construction as those described above for the basic batch meter shown in Figure 2 of the drawings. However, they are mounted on opposite sides of their respective quadrants 176 and 177 as is clearly shown in Figure 5 of the drawings. The quadrant levers 196 and 197 are provided with laterally extending arms 198 and 199. Each of the laterally extending arms are of sufficient length so that arm 198 is adapted to abut the locking rod trip 192 and arm 199 is adapted to abut locking rod trip 193.

The quadrant levers 196 and 197 are fixedly connected and rotatable with the quadrants 176 and 177 as above described in the basic batch meter shown in Figure 2 of the drawings and accordingly as one or the other of the quadrants 176 and 177 are rotated the lever arms 198 and 199 will engage its respective lever arm trip 192 or 193 so the cam face of one or the other of the cam stop members 194 or 195 will engage the end of the locking rod being contacted.

When this position is reached, the expansion of the setting bar springs (not shown) snaps the respective setting or locking bars 119 and 120, affected, to the non-engaged position so that the worm 160 or 161 is instantly disengaged from the respective gear teeth 178 or 179 on the quadrants.

This movement also frees one or the other of the quadrants 176 and 177 and allows them to rotate back to the predetermined stop position under action of gravity.

Since each of the setting or locking bars 119 and 120 are identical in construction with the member 8 in Figure 2 showing the basic batch meter for single drums, they will also be provided with springs (not shown) to reduce the shock effect of the releasing action.

Counting device

Since the material is moved from compartment 102 to compartment 103 only a single counting device is necessary to count the number of batches mixed in the dual mixing drum 101.

The counting device is substantially identical with that in the basic batch meter shown in Figures 2 and 3 and operates in conjunction with the portions of the modified batch meter connected with the first compartment 102.

Figure 5, accordingly shows a counting device 200 which is mounted on the inner wall of the housing 118 by means of a bracket 261. The counting device may be any suitable type, of which there are many easily purchasable on the open market, for registering by single unit. The locking rod 188 is connected to the counting device 200 by an elongated eccentric rod 202 connected between the upper end of the locking rod 188 and an actuating arm 203 on the counting device.

Each time the locking rod 188 is lifted to release the setting bar 119, one unit is registered on the counting device, each unit being the equivalent of one batch, whereby a count may

be maintained for the number of batches mixed in a period of time or for a particular job.

Auditory device

An auditory device is further provided for each compartment to notify the operator that the number of revolutions are completed. This includes a bell 204 mounted on the front cover which coacts with means (not shown) which are operated by the setting or locking bar 119. Similarly, a bell 205 is mounted on the rear wall of the housing 118 which coacts with means (not shown) which are operated by the setting or locking bar 120.

The means coacting with each of the setting bars 119 and 120 are identical with the various members coacting with the setting or locking bar 8 in the basic batch meter shown in Figures 2 and 3, and operate as above described with reference to these members.

While these forms of the invention have been illustrated and described, it will be understood that the invention is not to be limited to the specific construction or arrangements of parts shown but that they may be widely modified within the invention defined by the claims.

What is claimed is:

1. The combination with mixing apparatus including, at least one mixing drum, a charging means for said mixing drum, a transfer means for discharging mixed ingredients from said mixing drum, and lever means for controlling said transfer means of, a batch meter including, a housing, driving means connected for continuous rotation with said drum pivotally mounted in said housing and disposed transversely of the longitudinal line of said housing, a driven timing means disposed parallel to the longitudinal line of said drum and perpendicular to said driving means, a setting rod slidably mounted in said housing connected to said driving means and normally maintaining said driving means out of engagement with said driven timing means, a trip mechanism, said setting rod operated by the charging means to move said driving means into engagement with said driven timing means to set said trip mechanism and to lock said lever means in the set position, means on said driven timing means for releasing said trip mechanism after a predetermined number of revolutions of said drum, and means for returning said setting rod to the released position.

2. The combination with mixing apparatus including, at least one mixing drum, a charging means for said mixing drum, a transfer means for discharging mixed ingredients from said mixing drum and lever means for controlling said transfer means of, a batch meter including, a housing, driving means connected for continuous rotation with said drum pivotally mounted in said housing and disposed transversely of the longitudinal line of said housing, a driven timing means disposed parallel to the longitudinal line of said drum and perpendicular to said driving means, a setting rod slidably mounted in said housing connected to said driving means and normally maintaining said driving means out of engagement with said driven timing means, a trip mechanism, said setting rod operated by the charging means to move said driving means into engagement with said driven timing means to set said trip mechanism and to lock said lever means in the set position, adjustable stop means formed in said housing to just allow said driving means to engage said driven

timing means, means on said driven timing means for releasing said trip mechanism after a predetermined number of revolutions of said drum, and means for returning said setting rod to the released position.

3. In the combination as claimed in claim 2 wherein said adjustable stop means comprises a lateral projection on said driving means, an adjustable threaded member mounted in said housing to abut said lateral projection on movement of said driving means by said setting rod, and a locking nut to hold the threaded member in the adjusted position.

4. The combination with mixing apparatus including, at least one mixing drum, a charging means for said mixing drum, a transfer means for discharging mixed ingredients from said mixing drum, and lever means for controlling said transfer means of, a batch meter including, a housing, driving means connected for continuous rotation with said drum pivotally mounted in said housing and disposed transversely of the longitudinal line of said housing, a driven timing means disposed parallel to the longitudinal line of said drum and perpendicular to said driving means, a setting rod slidably mounted in said housing connected to said driving means and normally maintaining said driving means out of engagement with said driven timing means, a trip mechanism, said setting rod operated by the charging means to move said driving means into engagement with said driven timing means to set said trip mechanism and to lock said lever means in the set position, adjustable stop means formed in said housing to just allow said driving means to engage said driven timing means, means on said driven timing means for releasing said trip mechanism after a predetermined number of revolutions of said drum, means for returning said setting rod to the released position, and a counting device to register each batch mixed including a mechanical counter having an actuating arm, an elongated lever connected between said actuating arm and the end of said trip mechanism remote from said setting rod and actuated by the release of said trip mechanism.

5. The combination with mixing apparatus including, at least one mixing drum, a charging means for said mixing drum, a transfer means for discharging mixed ingredients from said mixing drum, and lever means for controlling said transfer means of, a batch meter including, a housing, a transverse shaft mounted in said housing and connected for continuous rotation with said drum, a driving means rotated by said transverse shaft and mounted thereon for movement in an arc having the axial line of said transverse shaft as its center, a freely rotatable driven timing quadrant having teeth on the outer periphery thereof perpendicular to the axial line of the driving means, a setting rod slidably mounted in said housing connected to said driving means and normally maintaining said driving means in the released position, said setting rod operated by said charging means to move the driving means into the set position for engagement with the teeth of said driven timing quadrant and to lock said lever means, a trip mechanism set by movement of said setting bar and released by said driven timing quadrant after a predetermined number of revolutions of said drum, and means for returning the setting rod to the released position.

6. The combination with mixing apparatus including, at least one mixing drum, a charging

means for said mixing drum, a transfer means for discharging mixed ingredients from said mixing drum, and lever means for controlling said transfer means of, a batch meter including a 5 housing, a transverse shaft mounted in said housing and connected for continuous rotation with said mixing drum, a worm shaft support mounted on said transverse shaft for movement in an arc having the axial line of said transverse shaft as its center, a worm shaft provided with a worm member thereon mounted on said worm shaft support and disposed perpendicular to the axial line of the transverse shaft and rotated continuously therewith, a freely rotatable driven timing quadrant having teeth on the outer periphery thereof perpendicular to the axial line of the worm shaft, a setting rod slidably mounted in said housing connected to said worm shaft support and normally maintaining said worm member out of engagement with the teeth of said driven quadrant, said setting bar operated by the charging means to move the worm shaft support into the set position so that the worm member will engage the teeth of the driven quadrant and to lock the lever means, a trip mechanism set by said movement of the setting bar, means on said driven quadrant for releasing said trip mechanism after a predetermined number of revolutions of said drum, and means for returning the setting bar to the released position.

7. In the combination as claimed in claim 6 wherein the means for releasing the trip mechanism includes, a quadrant lever, said quadrant lever connected at its central portion to said quadrant and movable therewith, and a lever arm formed on said quadrant lever extending laterally to contact and move said trip mechanism.

8. The combination with mixing apparatus including, at least one mixing drum, a charging 40 means for said mixing drum, a transfer means for discharging mixed ingredients from said mixing drum, and lever means for controlling said transfer means of, a batch meter including a housing, a transverse shaft mounted in said housing and connected for continuous rotation with said mixing drum, a worm shaft support mounted on said transverse shaft for movement in an arc having the axial line of said transverse shaft as its center, a worm shaft provided with a worm member thereon mounted on said worm shaft support and disposed perpendicular to the axial line of the transverse shaft and rotated continuously therewith, a freely rotatable driven timing quadrant having teeth on the outer periphery thereof perpendicular to the axial line of the worm shaft, a setting rod slidably mounted in said housing connected to said worm shaft support and normally maintaining said worm member out of engagement with the teeth of said driven quadrant, said setting bar operated by the charging means to move the worm shaft support into the set position so that the worm member will engage the teeth of the driven quadrant and to lock the lever means, a trip mechanism set by said movement of the setting bar, means on said driven quadrant for releasing said trip mechanism after a predetermined number of revolutions of said drum, adjustable stop means formed in said housing to just allow said worm to engage the teeth on said driven timing quadrant, means on said driven timing quadrant for releasing said trip mechanism after a predetermined number of revolutions of said drum, and means for returning said setting rod to the released position.

15

9. In the combination as claimed in claim 8 wherein said adjustable stop means comprises a lateral projection on said worm shaft support, an adjustable threaded member mounted in said housing to abut said lateral projection on movement of said worm shaft support by the setting rod, and a locking nut to hold the threaded member in the adjusted position.

10. A batch meter comprising a housing, a continuously rotating shaft disposed transversely of the longitudinal dimension in said housing, driving means connected for continuous rotation with said shaft and mounted on said shaft for movement in an arc having the axial line of said shaft as its center, driven timing member disposed parallel to the longitudinal line of said housing and perpendicular to said driving means, a setting rod slidably mounted in said housing and connected to said driving means for moving it into and out of engagement with said driven timing member, a tripping mechanism coacting with said setting rod when it moves the driving means into the engaged position and to hold it in this position until released, and means on said driven timing member to release the tripping mechanism after a pre-determined number of revolutions of said driving means to allow said setting bar to move to the released position.

11. A batch meter comprising a housing, a continuously rotating shaft disposed transversely of the longitudinal dimension in said housing, driving means connected for continuous rotation with said shaft and mounted on said shaft for movement in an arc having the axial line of said shaft as its center, driven timing member disposed parallel to the longitudinal line of said housing and perpendicular to said driving means, a setting rod slidably mounted in said housing and connected to said driving means for moving it into and out of engagement with said driven timing member, a tripping mechanism coacting with said setting rod when it moves the driving means into the engaged position and to hold it in this position until released, an adjustable stop means including a lateral projection on said driving means, an adjustable threaded member mounted in said housing to abut said lateral projection on movement of said driving means to just allow said driving means to engage said driven timing member, and a locking nut to hold said threaded member in its adjusted position, and means on said driven timing member to release the tripping mechanism to allow said setting rod to move to the released position.

12. A batch meter comprising a housing, a continuously rotating shaft disposed transversely of the longitudinal dimension in said housing, driving means connected for continuous rotation with said shaft and mounted on said shaft for movement in an arc having the axial line of said shaft as its center, driven timing member disposed parallel to the longitudinal line of said housing and perpendicular to said driving means, a setting rod slidably mounted in said housing and connected to said driving means for moving it into and out of engagement with said driven timing member, a tripping mechanism coacting with said setting rod when it moves the driving means into the engaged position and to hold it in this position until release, and means on said driven timing member to release the tripping mechanism after a predetermined number of revolutions of said driving means to allow said setting bar to move to the released position, and a counting device to register each batch mixed

16

including a mechanical counter having an actuating arm, an elongated lever connected between said actuating arm and the end of said trip mechanism remote from said setting bar and actuated by the release of said trip mechanism.

13. The combination with mixing apparatus including, a plurality of rotatable mixing compartments, a charging means for at least one of said compartments, a transfer means for discharging mixed ingredients from one compartment to the other, a discharge member for at least another compartment, a lever means for controlling said transfer means, and a second lever means for controlling said discharge member of a batch meter including a housing, a driving means for each compartment in said housing connected for continuous rotation with its respective mixing compartment and disposed parallel to each other and transversely of the longitudinal line of said housing, a driven timing member for each compartment each disposed parallel to the longitudinal line of said housing and to each other and perpendicular to its respective driving means, setting bars slidably mounted in said housing in spaced relation whereby each is in alignment with its respective driving means and is connected thereto for normally maintaining the driving means out of engagement with said driven timing members, a trip mechanism for each of said setting rods, one of said setting rods operated by said charging means and another of said setting rods operated by said transfer means on release of said setting rod operated by said charging means, to allow said setting bars to move its respective driving means into engagement with its related driven timing means, to set its trip mechanism and to lock the lever means controlling the transfer means and the discharge means of the compartment under operation, means on each of said driven timing members for releasing its respective trip mechanism after a predetermined number of revolutions of said drum, and means for returning each of said setting rods to its released position when the trip mechanisms are so operated.

14. The combination with mixing apparatus including, a plurality of rotatable mixing compartments, a charging means for at least one of said compartments, a transfer means for discharging mixed ingredients from one compartment to the other, a discharge member for at least another compartment, a lever means for controlling said transfer means, and a second lever means for controlling said discharge member of a batch meter including a housing, a driving means for each compartment in said housing connected for continuous rotation with its respective mixing compartment and disposed parallel to each other and transversely of the longitudinal line of said housing, a driven timing member for each compartment each disposed parallel to the longitudinal line of said housing and to each other and perpendicular to its respective driving means, setting bars slidably mounted in said housing in spaced relation whereby each is in alignment with its respective driving means and is connected thereto for normally maintaining the driving means out of engagement with said driven timing members, a trip mechanism for each of said setting rods, one of said setting rods operated by said charging means and another of said setting rods operated by said transfer means on release of said setting rod operated by said charging means, to allow said setting bars to move its re-

spective driving means into engagement with its related driven timing means, to set its trip mechanism and to lock the lever means controlling the transfer means and the discharge means of the compartment under operation, adjustable stop means formed in said housing to just allow each of said driving means to engage said driven timing members, means on each of said driven timing members for releasing its respective trip mechanism after a predetermined number of revolutions of said drum, and means for returning each of said setting rods to its released position when the trip mechanism is released.

15. In the combination as claimed in claim 14 wherein said adjustable stop means comprises a laterally disposed projection on each of said driving means, adjustable threaded members mounted in said housing each adapted to abut at least one of said lateral projections on movement of said driving means by said setting rod, and locking nuts to hold each threaded member in the adjusted position.

16. The combination with mixing apparatus including a rotatable mixing drum having a first and a second compartment for mixing ingredients therein, charging means for said mixing drum, a transfer chute for transferring mixed ingredients from one compartment to the other, a discharge member for discharging mixed ingredients from said mixing drum, a lever means for controlling said transfer chute, and second lever means for controlling said discharge member of a batch meter including a housing, a transverse shaft mounted in said housing and connected for continuous rotation with said mixing drum, a first and a second worm shaft support mounted on said transverse shaft in spaced relation to each other and for movement in parallel arcs having the axial line of said transverse shafts as its center, a worm shaft on each of said worm shaft supports provided with a worm member thereon, said worm shafts disposed perpendicular to the axial line of the transverse shaft and connected thereto for continuous rotation therewith, freely rotatable driven timing segments for each of said worm shaft supports and each having teeth on the outer periphery thereof perpendicular to the axial line of the worm shaft, a first and a second setting rod slidably mounted in said housing and connected to said first and second worm shaft supports for normally maintaining said worm shaft supports out of engagement with the teeth of its respective driven timing quadrant, said first setting rod operated by said charging means to move the first worm shaft support into engagement with its respective driven timing quadrant and to lock the lever means for controlling the transfer chute, said second setting rod operated by release of said transfer chute to move the second worm shaft support into engagement with its driven timing quadrant and to lock the second lever means for controlling the discharge member, a trip mechanism for each setting rod set by movement of said rod, means on each of said driven timing quadrants for releasing its respective trip mechanism after a predetermined number of revolutions of said drum, and means for returning the setting rods to their released position when the trip mechanism is released.

17. In the combination as claimed in claim 16 wherein the means on each driven timing quadrant for releasing the tripping mechanism includes, quadrant levers, said quadrant levers connected at their central portions to said driven

timing quadrants and movable therewith, and lever arms formed on said quadrant levers extending laterally to contact and move the respective trip mechanism for that quadrant.

5. 18. The combination with mixing apparatus including a rotatable mixing drum having a first and a second compartment for mixing ingredients therein, charging means for said mixing drum, a transfer chute for transferring mixed ingredients from one compartment to the other, a discharge member for discharging mixed ingredients from said mixing drum, a lever means for controlling said transfer chute, and second lever means for controlling said discharge member of a batch meter including a housing, a transverse shaft mounted in said housing and connected for continuous rotation with said mixing drum, a first and a second worm shaft support mounted on said transverse shaft in spaced relation to each other and for movement in parallel arcs having the axial line of said transverse shafts as its center, a worm shaft on each of said worm shaft supports provided with a worm member thereon, said worm shafts disposed perpendicular to the axial line of the transverse shaft and connected thereto for continuous rotation therewith, freely rotatable driven timing segments for each of said worm shaft supports and each having teeth on the outer periphery thereof perpendicular to the axial line of the worm shaft, a first and a second setting rod slidably mounted in said housing and connected to said first and second worm shaft supports for normally maintaining said worm shaft supports out of engagement with the teeth of its respective driven timing quadrant, said first setting rod operated by said charging means to move the first worm shaft support into engagement with its respective driven timing quadrant and to lock the lever means for controlling the transfer chute, said second setting rod operated by release of said transfer chute to move the second worm shaft support into engagement with its driven timing quadrant and to lock the second lever means for controlling the discharge member, adjustable stop means formed in said housing to just allow said worms to engage the teeth on said driven timing quadrants, a trip mechanism for each setting rod set by movement of said rod, means on each of said driven timing quadrants for releasing its respective trip mechanism after a predetermined number of revolutions of said drum, and means for returning the setting rods to their released position when the trip mechanism is released.

55. 19. In the combination as claimed in claim 18 wherein said adjustable stop means comprises a lateral projection on each of said worm shaft supports, adjustable threaded members mounted in said housing each adapted to abut at least one of said lateral projections on movement of said driving means by said setting rod, and a locking nut for each of said threaded means for holding the same in adjusted position.

65. 20. A batch meter comprising a housing, a continuously rotating shaft disposed transversely of the longitudinal line of said housing, a plurality of driving means connected to said transverse shaft for continuous rotation therewith and mounted thereon in spaced relation for movement in parallel arcs having the axial line of said transverse shaft as centers, a driven timing means for each of said driving means disposed parallel to the longitudinal line of said housing and to each other and perpendicular to the driving means, a

plurality of setting rods slidably mounted in said housing one for each driving means and connected to said driving means for moving said driving means into engagement with said driven timing members, a tripping mechanism coacting with each of said setting rods when it moves the driving means into engagement and to hold them in this position until released, and means on each of said driven timing members to release its respective tripping mechanism after a predetermined number of revolutions of said driving members to allow said setting bar to be moved to the released position.

21. A batch meter comprising a housing, a continuously rotating shaft disposed transversely of the longitudinal line of said housing, a first and a second worm shaft support mounted on said transverse shaft in spaced relation for movement in parallel arcs having the axial line of said transverse shaft as centers, worm shafts having worm members thereon on each of said worm shaft supports disposed perpendicular to the axial line of the transverse shaft and connected thereto for continuous rotation therewith, driven timing quadrants for each of said worm members disposed parallel to the longitudinal line of said housing and to each other and having teeth on the outer periphery perpendicular to the axial line of said worms, a first and a second setting rod for each of said worm shaft supports slidably mounted in said housing and connected to said worm shaft supports to move the worms into engagement with the teeth of its respective driven timing quadrant, a tripping mechanism coacting with each of said setting rods when it moves the worm shaft support to the engaged position and to hold them in this position until released, adjustable stop means including lateral projections on each of said worm shaft supports, adjustable threaded members mounted in said housing and to abut its respective lateral projection on movement by the setting rod to just allow said worm to engage the teeth of said driven timing quadrant, and a locking nut for each of said threaded members to hold said threaded members in their adjusted position, and means on each of said driven timing members to release its respective tripping mechanism after a predetermined number of revolutions of its driving means to allow the setting rod to return to the released position.

22. A batch meter comprising a housing, a continuously rotating shaft disposed transversely of the longitudinal line of said housing, a first and a second worm shaft support mounted on said transverse shaft in spaced relation for movement in parallel arcs having the axial line of said transverse shaft as centers, worm shafts having worm members thereon on each of said worm shaft sup-

ports disposed perpendicular to the axial line of the transverse shaft and connected thereto for continuous rotation therewith, driven timing quadrants for each of said worm members disposed parallel to the longitudinal line of said housing and to each other and having teeth on the outer periphery perpendicular to the axial line of said worms, a first and a second setting rod for each of said worm shaft supports slidably mounted in said housing and connected to said worm shaft supports to move the worms into engagement with the teeth of its respective driven timing quadrant, a tripping mechanism coacting with each of said setting rods when it moves the worm shaft support to the engaged position and to hold them in this position until released, adjustable stop means including lateral projections on each of said worm shaft supports, adjustable threaded members mounted in said housing and to abut its respective lateral projection on movement by the setting rod to just allow said worm to engage the teeth of said driven timing quadrant, and a locking nut for each of said threaded members to hold said threaded members in their adjusted position, and means on each of said driven timing members to release its respective tripping mechanism after a predetermined number of revolutions of its driving means to allow the setting rod to return to the released position.

23. In the combination as claimed in claim 22 wherein the means on each driven timing quadrant for releasing the tripping mechanism includes, quadrant levers, said quadrant levers connected at their central portions to said driven timing quadrants and movable therewith, and lever arms formed on said quadrant levers extending laterally to contact and move the trip mechanism on rotation of the driven timing quadrant by the worms.

ALFRED W. SLACK.
ROBERT A. SNYDER.
